US0D1063951S

(12) **United States Design Patent** (10) Patent No.: **US D1,063,951 S**
(45) Date of Patent: ** Feb. 25, 2025

(54) **DISPLAY SCREEN WITH GRAPHICAL USER INTERFACE**

(71) Applicant: **IGT**, Las Vegas, NV (US)

(72) Inventors: **Amber Hughes**, Reno, NV (US);
Zachary Cooper, Las Vegas, NV (US)

(73) Assignee: **IGT**, Las Vegas, NV (US)

(**) Term: **15 Years**

(21) Appl. No.: **29/809,656**

(22) Filed: **Sep. 29, 2021**

(51) LOC (15) Cl. **14-04**

(52) U.S. Cl.
USPC **D14/485**

(57) **CLAIM**

The ornamental design for a display screen with graphical user interface as shown and described.

DESCRIPTION

The patent or application file contains at least one drawing executed in color. Copies of this patent with color drawing(s) will be provided by the Office upon request and payment of the necessary fee.

The sole FIGURE is a front view of a display screen with graphical user interface of our new design.

The outermost broken lines in the drawing shows the display screen which forms no part of the claimed design. The remaining broken lines showing portions of the graphical user interface form no part of the claimed design.

1 Claim, 1 Drawing Sheet
